UNITED STATES PATENT OFFICE.

WILHELM C. BERLING, OF BUFFALO, NEW YORK.

COMBINATION MAGNETO-GENERATOR.

1,165,221.

Specification of Letters Patent. Patented Dec. 21, 1915.

Application filed December 12, 1913. Serial No. 806,206.

To all whom it may concern:

Be it known that I, WILHELM C. BERLING, a subject of the King of Sweden, residing at Buffalo, in the county of Erie and State of 5 New York, have invented new and useful Improvements in Combination Magneto-Generators, of which the following is a specification.

This invention relates to a combination 10 igniting and lighting magneto or electric generator designed more particularly for motor cycles.

Heretofore such machines have been equipped with separate magnetos mounted 15 on independent supports and each having its own driving mechanism.

The object of my invention is to combine an igniting generator and a lighting generator in a single unit, thus simplifying the 20 device and furnishing a compact, unitary structure which can be readily mounted in place of the ordinary ignition magneto and driven from the same shaft.

In the accompanying drawings: Figure 1 25 is a central longitudinal section of the improved magneto. Fig. 2 is an elevation of the front or driving end of the machine. Fig. 3 is a similar view omitting the front head of the casing and showing the lower 30 armature shaft in cross section. Fig. 4 is an elevation of the rear end of the machine. Fig. 5 is a fragmentary top plan view thereof. Fig. 6 is a fragmentary transverse section on line 6—6, Fig. 1.

Similar characters of reference indicate 35 corresponding parts throughout the several views.

1 indicates the base of the machine upon 40 which is rigidly mounted a frame or casing 2 which incloses the armatures 3 and 4 and associated parts of the igniting and lighting generators. This casing may be of any suitable construction. In the preferred construction illustrated in the drawings, the 45 armature 3 of the lighting generator is disposed directly above and parallel with the armature 4 of the ignition generator, and the walls of the casing follow the curvature of the armature, forming approximately cylindrical upper and lower portions, as best 50 shown in Fig. 4. The ends of the casing are closed by removable heads 5 and 6.

As shown in Fig. 1, the armatures are 55 journaled in suitable anti-friction bearings, in the upper and lower portions of the cas-

ing. The ignition or high tension generator has a current interrupter 7 and a collector-ring 8 of any suitable or conventional form, while the lighting generator has a suitable collector-ring 9.

As seen in Fig. 1, the upper and lower armatures are offset or vertically out of alignment. 10 indicates the permanent magnets of the lower armature and 11 the corresponding magnets of the upper armature, 60 the two sets of magnets being reversely arranged to bring their poles opposite the companion armatures. The legs of the magnets embrace the walls of the casing and bear against pole-pieces 12 secured in openings in 65 said walls, as shown in Fig. 6. Suitable straps 13 and 14 serve to securely hold the magnets in place.

The shaft of one of the armatures, preferably that of the ignition generator, is extended through the end of the casing and carries a driving gear or wheel 15 and also a second gear wheel 16 arranged within the casing and meshing with a pinion 17 mounted on the shaft of the upper armature 3. By 75 this construction and arrangement the upper armature is driven directly from the lower armature, dispensing with a separate drive for the same.

To permit the lighting generator to be 80 thrown out of gear during the day-time, the pinion 17 is preferably movable out of engagement with the gear wheel 16. For this purpose, this pinion is mounted to slide endwise on the upper armature shaft and normally held in gear with the wheel 16 by a spring 18 surrounding said shaft between the flanged hub 19 of the pinion and the opposing race-ring 20. The pinion is shifted out of gear with the wheel 16 by a slide 21 90 guided in a longitudinal groove 22 in the top of the casing and confined therein by a plate 23 secured to the casing. As shown in Fig. 1, this slide is provided in its underside with a fork 24 which engages the flanged hub 19 of the pinion 17, and in its upper side with a shifting pin or projection 25 which projects through a longitudinal slot 26 in the plate 23. Preferably combined with this pin and surrounding it is a vertically-movable locking sleeve 27 adapted to interlock with one or the other of a pair of circular enlargements 28 at opposite ends of the slot 26. This sleeve is constantly urged downwardly on the pin 25 by a spring 100 105 110

29 which surrounds the pin between a head or shoulder 30 thereof and an inturned-flange 31 at the base of the sleeve. When the pinion 17 is in proper engagement with 5 the gear wheel 16, the spring-pressed sleeve is seated in the outer enlargement 28, as shown in the drawings, positively locking the pinion in that position. To shift the pinion out of gear, said sleeve is withdrawn 10 from said enlargement and the slide 21 is pushed rearwardly by means of the sleeve until the latter snaps into the rear enlargement 28, thereby locking the pinion in its inoperative position.

15 This improved combination igniting and lighting magneto affords a number of important advantages. As both generators are combined in a single compact unit, the device can be mounted on a motor cycle on the 20 same bracket or support as the ordinary high-tension magneto and driven from the same shaft. This enables manufacturers of motor cycles to adopt or substitute this improved magneto for the ordinary separate 25 magnetos without requiring any change, re-arrangement or re-construction of the parts of their machines. This unitary construction is moreover lighter and less expensive than two separate magnetos and requires the manufacturer to keep only one 30 kind on hand, instead of two. The combination of the two generators in such manner that one is driven from the other also simplifies the construction and reduces the cost 35 of the driving mechanism, as well as facilitates the installation of the device.

I claim as my invention:

1. A combination magneto, comprising a single frame or support, an igniting generator and a lighting generator both mounted in said frame, and means for driving the lighting generator from the igniting generator, said driving means including members movable into and out of gear with each other. 40

2. A combination magneto, comprising a single frame or support, an igniting generator and a lighting generator both mounted in said frame, the armature-shafts of said generators being parallel with each other, 45 intermeshing gear-wheels mounted on said shafts, one of said gear wheels being slideable on its shaft to move into and out of gear with the wheel of the other armature-shaft, and means for driving the last-named 50 shaft. 55

3. A combination magneto, comprising a single frame or support, an igniting generator and a lighting generator both mounted in said frame, the rotary armatures of said 60 generators being arranged one above the other and offset laterally, reversely arranged permanent magnets arranged side by side and associated with the respective armatures, and means for driving one of said 65 armatures from the other.

Witness my hand this 9th day of December, 1913.

WILHELM C. BERLING.
